SECTIONAL CONTAINER FOR HOLDING
CUTTING DIES AND TAGS

James Donald Lockwood, Endicott, N. Y.

Application October 17, 1947, Serial No. 780,384

6 Claims. (Cl. 211—86)

1

This invention is a novel sectional container for holding cutting dies and tags within the container in convenient positions, which dies and tags are needed in the process of cutting shoe upper blanks, or the like, the same increasing the efficiency of handling the dies.

At the present time, a great deal of time is lost in handling cutting dies due to the fact that the operator usually has several sizes on a job, which sizes are bound to become mixed. The normal operating of cutting shoe and other blanks necessitates the operator going to a die-rack to select the proper dies and bringing them to his machine, piling the dies on the block. Most cutting dies are double-edged and thus the piling of such dies on the block results in damage to one or both cutting edges. When he changes sizes he loses time by having to sort the dies over to obtain the right size. He loses more time when putting them back in the rack because he has to sort them again. When the cripple-cutter wants a die for making a cut, more time is lost in the same manner. Moreover, in cases where has a pattern with several pieces to a pair, considerable block space is required to take care of the dies. More block space is again wasted when he spreads the tags out thereon as is customary. Having dies and tags scattered on the block in this manner gives the room a disorderly appearance, and also creates a certain amount of confusion which hampers the cutter in his work.

Most of this loss and waste of time and effort can be eliminated or materially reduced by the use of my cutter's die-box having sections which may be numbered by the same system now used on the die-racks, making it very simple to shift dies from the racks to the box or vice-versa.

The principal object of my invention is to provide a cutter's die box adapted to be suspended from a cutting machine, the same having means for keeping all of the dies needed by the cutter, in proper order, off but adjacent to the work block, and thus in a convenient position, the dies being free from the hazard of becoming dulled by their cutting edges being rubbed together.

Other objects of my invention are: to provide a sectional container for cutting dies, the use of which will make all table and block space available for actual cutting; will keep the various sizes of dies separated, thereby eliminating one of the main causes of dulling of the dies due to rubbing of the edges together; will speed production, reducing the time required to change dies because the dies are kept in proper order in the container; will retain the dies in proper order di-

2

rectly in front of the operator so that the operator can tell at a glance, without stopping work, whether he has a particular die needed by another cutter or by a cripple-cutter; will maintain a more orderly appearance in the cutting room by keeping the tags and dies, not in use, off of the tables and blocks; will reduce materially the number of mistakes especially where one part or parts of a shoe are cut up or down from the rest, as the dies can be arranged in the box in the order they are to be used; will provide a flexible pocket in the upper section of the container serving as a convenient place to keep the tags so that they need not be tied up while they are out of the cutter's way; will provide a hanger for the sectional container, constructed in such a manner that it will swing in the event the container is hit by a cutting arm, or in event the operator wants to get dies from the container without bothering the cutter; will provide a hanger which can be lifted off the cutting machine for cleaning, or when the machine is needed for repair or when the block needs planing; also, will provide a sectional container which can be taken to the rack and filled with dies, putting them in the container in order, thus saving sorting of the dies at the machine.

I will explain the invention with reference to the accompanying drawings, which illustrate one practical embodiment thereof, to enable others familiar with the art to adopt and use the same; and will summarize in the claims the novel features of construction and novel combinations of parts for which protection is desired.

In said drawings:

Fig. 1 is a front elevation showing my novel sectional container mounted upon a cutting machine.

Fig. 2 is a perspective view of the holder for the sectional container, detached.

Fig. 3 is a front elevation of the holder shown in Fig. 2.

Fig. 4 is a perspective view of the sectional container, detached, showing the partitions for separating the dies, and showing tags inserted in the rubber pocket.

Fig. 5 is a top plan view of one end of the container, showing tags positioned in the rubber pocket.

Fig. 6 is a detailed section.

The shoe cutting machine A (Fig. 1) is provided with a block B, having an upper casting C, provided with a hole (not shown) in one side whereby the tripping device of the machine may be oiled, the hole also serving as a means for

suspending the holder on the side of the machine. Usually the upper casing C is substantially cylindrical adjacent the bench B. The construction of the cutting machine, upper casting C, and bench B is well known and forms no part of my present invention.

As shown in Figs. 1, 4 and 5, my sectional container is preferably of rectangular shape, the same being provided with a front 1, a back 2, side walls 3, and bottom 5, the container being of substantial depth, and being provided with handles 4 at the tops of the sides 3 whereby the container may be readily lifted or transferred. A series of spaced vertical partitions 6 is provided within the container, extending from the bottom 5 to the upper edges of the side walls 3, the same preferably having their ends dadoed into the side walls and bottom of the container. The spaces between the partitions 6 and the front wall 1 of the container are adapted to hold shoe or other cutting dies, which may be single edged or double edged, the dies being placed in proper order of use therein and the partitions keeping the dies in adjacent rows separated and spaced apart so that their cutting edges will not become dulled by rubbing together. If desired, the walls and partitions of the container may be made of wood, "Masonite," or other thin material having a requisite strength.

Between the rear wall 2 of the container and the adjacent partition 6 is a flat rubber strip 7 (Figs. 4 and 5) normally lying along the inner face of wall 2 and having its ends bent as at 7a toward the partition, the bent ends being clamped in position by means of clips 8, secured by bolts 9 or the like to the sides 3 of the container, as shown in Figs. 4 and 5, the rubber strip 7 forming a flexible and extensible pocket adapted to hold bunches of tags T used in connection with the respective dies in the process of cutting.

The sectional container is held in position on the cutting machine A beside the upper casting C, same slanting at a convenient angle upwardly from the front wall 1 to the rear wall 2, as shown in Fig. 1, by means of a holder 10 of open rectangular shape, having upwardly extending side flanges 10a slightly larger than the outside measurements of the lower end of the sectional container, whereby the container may be readily lifted into or out of the holder 10, using the handles 4. At the end of holder 10, adjacent the upper casting C is a vertically disposed hanger 11, having a flange 11a at its upper end, adapted to overlie the top of upper casting C, the flange being provided with a stud 11b adapted to enter the oil hole in the top of the upper casting C, as shown in Fig. 2. The holder 10 is secured in angular position to the hanger 11 adjacent its mid point by means of screws or rivets 12 so that the holder will retain its angular position on the machine.

The lower end of hanger 11 projects below the holder 10 and is provided with a flange 11c parallel with the flange 11a, i. e., extending toward the upper casting C. Upon the flange 11c is a plate 13 having a circular recess 13a in its outer edge adapted to contact the curved side of the upper casting C. Plate 13 is maintained upon the flange 11c by means of rivets or screws 14, as shown more particularly in Fig. 6. In order to maintain the outer end of the holder 10 in horizontal position, a brace 15 is provided below the holder, having its outer end flanged as at 15a and secured by rivets 16 or the like to the flange 10a of the holder 10, the brace 15 sloping inwardly and downwardly to meet the lower end of

hanger 11 and having a flange 15b underlying the flange 11c, the same being secured thereto by the rivets 14 which secure the plate 13 to the flange 11c, brace 15 maintaining the holder 10 rigidly supported upon the hanger 11 to support the weight of the sectional container carried by the holder. Preferably, the holder 10 is made of angle-iron, although the same may be made of any other desired material and in any other desired manner.

I do not limit my invention to the exact form shown in the drawings, for obviously changes may be made therein within the scope of the claims.

I claim:

1. A die holder for use with a cutting machine for shoe upper parts or the like, having a block and having an upper casting with an oil hole in its top adjacent one side; comprising a hanger, the upper end thereof adapted to be secured to the casting, and the lower end of said hanger adapted to terminate above the said block; a member on said lower end of the hanger adapted to conform with and contact the adjacent wall of the upper casting, a holder frame having its inner side secured to the hanger intermediate its ends, said holder frame being inclined forwardly and downwardly; a brace underlying the holder frame and having its outer end secured to the outer side of the holder frame and having its inner end flanged and secured to the lower end of the hanger; and a container seating upon the holder and having a vertical series of spaced laterally disposed partitions therein adapted to receive cutting dies.

2. In a die holder as set forth in claim 1, a flexible strip within the container contacting the inner face of the rear wall thereof; and means securing the ends of the strip to the container; said strip forming a pocket adapted to receive bunches of tags used with the dies in the cutting operation.

3. In a die holder as set forth in claim 1, the upper end of the hanger adapted to overlie said hole; and securing means comprising a stud carried by said hanger and adapted to enter the said hole.

4. A die holder for use with a cutting machine for shoe upper parts or the like having a block and having an upper casting with an oil hole in its top adjacent one side; comprising a hanger, the upper end thereof adapted to be secured to the casting, and said hanger having its lower end flanged and adapted to terminate above the said block; a plate secured on said lower flange having a recess in its edge adapted to conform with and contact the wall of the upper casting; a rectangular holder frame having upstanding flanges and having its inner side secured to the hanger intermediate its ends, said holder frame sloping forwardly and downwardly; an inclined brace underlying the holder frame and having its outer end flanged and secured to the outer side of the holder frame and having its inner end flanged and secured to the lower flange of the hanger; a rectangular container seating upon the holder frame within the upstanding flanges thereof and having a vertical series of spaced laterally disposed partitions therein extending between the container sides and adapted to receive cutting dies and to maintain the dies in adjacent rows separated.

5. In a die holder as set forth in claim 4, the flexible and extensible strip within the container contacting the inner face of the rear wall thereof; and means securing the ends of the strip to

the sides of the container; said strip forming a pocket adapted to receive bunches of tags used with the dies in the cutting operation.

6. In a die holder as set forth in claim 4, the upper end of the hanger adapted to overlie said hole; and securing means comprising a stud carried by said hanger and adapted to enter said hole.
